F. E. TEN EYCK.
DISK VALVE MECHANISM.
APPLICATION FILED MAY 12, 1915.

1,184,272.

Patented May 23, 1916.

UNITED STATES PATENT OFFICE.

FRANK E. TEN EYCK, OF AUBURN, NEW YORK, ASSIGNOR TO AIR DEVICE MANUFACTURING COMPANY, OF CHICAGO, ILLINOIS, A CORPORATION OF MAINE.

DISK-VALVE MECHANISM.

1,184,272.

Specification of Letters Patent.

Patented May 23, 1916.

Application filed May 12, 1915. Serial No. 27,515.

To all whom it may concern:

Be it known that I, FRANK E. TEN EYCK, a citizen of the United States, residing at Auburn, in the county of Cayuga and State 5 of New York, have invented certain new and useful Improvements in Disk-Valve Mechanism; and I do hereby declare the following to be a full, clear, and exact description of the invention, such as will enable others skilled in the art to which it 10 appertains to make and use the same.

My invention consists in the novel features hereinafter set forth reference being had to the accompanying drawing which 15 illustrates two embodiments of the invention, selected by me for purposes of illustration, and the said invention is fully disclosed in the following description and claims.

20 Referring to the said drawings, Figure 1 represents a vertical sectional view of one embodiment of my invention designed more particularly for use as a distributor. Fig. 2 is a front elevation of the apparatus shown 25 in Fig. 1, with cover and valve removed. Fig. 3 is an elevation of the inner face of the disk valve proper. Fig. 4 is a top plan view, partly in section, of a different form or embodiment of my invention, adapted 30 more particularly for use as a controlling valve to be operated by hand or otherwise. Fig. 5 is a vertical sectional view of the same. Fig. 6 is a front elevation of the device shown in Figs. 4 and 5 with the cover 35 and valve removed. Fig. 7 is an elevation of the inner face of the disk valve.

My invention relates to disk valve mechanism adapted especially for use in connection with compressed fluid starting mechanism for internal combustion engines, such 40 for example, as is illustrated in my former applications for Letters Patent of the United States, Serial Nos. 844,611 filed June 12, 1914, and 22,551 filed April 20, 1915, 45 although this valve mechanism is not limited to use in a system of this kind.

In the drawing accompanying and forming a part of this application, I have shown two embodiments of the invention, selected 50 by me for purposes of illustration, the first form illustrated in Figs. 1, 2, and 3 being adapted for use particularly, although not necessarily, as a distributor for distributing compressed fluid to the several cylinders of 55 an internal combustion engine for starting

the same, in a predetermined manner, in which case the valve proper will ordinarily be rotatable, as shown, and operated by any suitable connections in timed relation with the crank shaft of the engine. 60 In the second embodiment of my invention, illustrated in Figs. 4 to 7 inclusive, the valve mechanism is adapted more particularly to serve as a controlling valve to be operated by hand or otherwise, and in this case the 65 valve proper oscillates instead of rotating as in the other form of the invention.

Referring to the form of my invention illustrated in Figs. 1, 2, 3, the valve casing or body 22 is provided with a cylindrical wall interiorly threaded near its outer edge, and with a plane circular inner or bottom face 23, which is preferably ground so as to be perfectly true, and is provided with one or more delivery ports or outlet ports 70 24. In this instance there are four ports 24 communicating by passages in the valve body with pipe connections 2^a, 3^a, 4^a, and 5^a, which, when the device is used as a distributor, lead to the several cylinders of the internal combustion engine. 21 represents the valve actuating shaft which has a portion extending through the valve body concentrically with the cylindrical portion 22 and preferably projecting slightly beyond the 75 inner ground face 23 of the valve body. The inner end of the shaft 21 is provided with means to interlock with the valve proper in order that the latter may rotate with the shaft, and in this instance I have 80 shown the shaft provided with a pair of circular holes or recesses 27 in its inner face, located on opposite sides of the axis of the shaft. The valve body is also provided with an annular recess 33 surrounding the 85 inner end of the shaft. The disk or valve proper is indicated at 25, and the inner face 26 thereof, which is shown in Fig. 3, is ground to fit the ground face 23 of the valve casing and is provided with a central cylindrical recess 29 to fit over the end of the shaft 21, and the valve is provided with interlocking devices for engaging the shaft, comprising in this instance, a pair of pins 28 extending into the recess 29 and adapted 90 to engage the recess 27 in the end of the shaft. The general shape of the valve proper is that of a circular plate or disk, but the exterior face of the valve is provided with a thickened central portion 100 105 110

forming a hub or boss 25^a, preferably circular in cross section. The plate portion of the valve outside of the hub is provided with a port or aperture 30 extending entirely through the disk or valve, and the inner face 26 is also provided with a recess 31 located at about the same distance from the center or axis of the valve as the aperture 30 and connected by a recess or passage 32 which extends toward the center of the face 26, in this instance, to the recess 29, but it is sufficient if it extends far enough toward the center to have its inner end coincide with the recess 33.

15 The outer end of the valve casing is closed, preferably by means of a screw cap or cover 36, which is preferably provided with a central aperture threaded to receive a supply pipe 38, and the hub or boss 25^a is so constructed that it does not extend to the inner face of the cap or cover. Before the cover is screwed on a spiral spring 35 is placed around the boss 25^a so that the inner end of the spring will engage the outer 20 plate portion of the valve, while the outer end of the spring will engage the inner face of the cap or cover, thus serving to hold the ground face 26 of the valve in frictional and fluid tight engagement with the ground 25 face 23 of the valve body, while permitting the valve to be rotated by means of the shaft 21. The valve being removable from the shaft and connected thereto by interlocking means, it can be readily removed 30 from the casing when desired for regrinding or other purposes, and it is not essential to secure the perfect perpendicularity of the shaft 21 with the plane of the ground faces 23 and 26 as the interlocking connections between the valve and shaft will accommodate variations therefrom and still permit the valve to be maintained in proper relation with the ground face of the casing. The valve body is also provided with a relief passage 34 extending from the annular recess 33 to the exterior of the valve casing and communicating with the atmosphere, as shown in Figs. 1 and 2, for the purpose of 40 permitting an outward discharge or relief 45 from the ports of the valve body through the recess 31 and passage 32 in the face of the disk valve.

When this device is used as a distributor, it will be understood that the shaft 21 will 50 be operated in timed relation with the crank shaft of the engine. The compressed fluid will be admitted through pipe 38 to the interior of the valve casing and will be distributed through the aperture 30 in the 55 valve to the successive ports 24 as the valve rotates, and thence to the appropriate cylinder of the explosive engine with which the apparatus is used. I prefer to locate the centers of the aperture 30 and the recess 31 60 at the same distance apart as two of the

ports 24 and to locate the recess 31 in advance of the aperture 30 as shown, so that, as the valve is rotated, when the aperture 30 is over one port 24, the recess 31 will be over the preceding port, which will be in communication with a cylinder which is next in firing order, and which is compressing, thus permitting the exhaust or relief of pressure in that cylinder through the recess 31, passage 32, annular recess 33, and relief aperture 34, as will be readily understood.

In the form of my invention shown in Figs. 4 to 7 inclusive, the body of the valve casing is provided with a cylindrical wall 60 having an internally threaded portion near its outer edge and having an inner ground circular face 61 to engage the inner ground face of the disk valve 65, which is constructed with an exterior central boss 65^c. 80 The inner face of the valve body is provided in this instance with two ports 62 and 63 which are connected respectively by passages with the pipes 18 and 38. The valve 65 is provided with two apertures 62^a and 63^a through the disk or plate portion thereof, and its inner face is also provided with a central recess 65^d and with recessed portions 65^a and 65^b communicating in this instance with the central recess 65^d and forming the 90 relief recess or recesses.

70 represents the actuating shaft for the valve, which is provided with an enlarged portion within the valve body having formed therein an annular recess 70^b and 100 provided with a longitudinal groove or recess 70^a communicating therewith and extending through to the inner end of the shaft. The inner end of the shaft and the disk valve are provided with interlocking 105 means, in this instance pin 71, projecting from the valve and extending into recesses in the inner face of the shaft.

In using this device as a controlling valve, I prefer to oscillate it instead of rotate it, 110 and to provide means for limiting the movement of the valve in both directions. In this instance I have shown the shaft 70 provided with a sleeve 110 adjacent to the rear portion of the valve body, said sleeve being 115 rigidly secured to the shaft 70 by set screws 110^a and the sleeve being provided with a stop lug or pin 111 projecting from the inner end of the sleeve, and adapted to engage stop shoulders 112 formed on the adjacent portions of the valve casing.

In some instances it is desirable to make the shaft 70 in two sections, to wit, a short section extending into the valve casing and a longer section united thereto and extending to some point where an actuating arm or other hand operated or other device is to be applied for oscillating the shaft, and as the length of the exterior portion of the shaft may vary in different situations in 130

which the valve is used, it is convenient to make the shaft in two parts as here shown, in which case the sleeve 110 may be applied to the inner section of the shaft 5 and secured thereto by one of the set screws 110^a and the exterior portion of the shaft may be inserted in the other end of the sleeve and held in relation to the sleeve and the other section of the shaft by the other 10 set screw 110^a, so that the sleeve will also act as a coupler, but this is not essential to the invention. In some instances it is desirable to attach a pressure gage to the controlling valve, and for this purpose I conveniently provide the valve casing with a 15 screw threaded aperture at its upper end to receive a pipe 109 as shown, which may lead to the pressure gage, the said threaded aperture being connected by a passage 64 with the interior of the valve casing. If 20 the pressure gage is not desired, the aperture and passage 64 can be closed by a plug. The valve body is also provided with a relief passage 60^a which communicates 25 with the annular recess 70^b and longitudinal recess 70^a, and hence with the relief recesses 65^a and 65^b in the face of the valve 65. The valve body is also provided with a closure or cover 67 which screws into the threaded 30 portion of the annular wall 60 and is provided with a centrally threaded opening to receive the inlet pipe 80, which may be connected with a source of compressed fluid. A coil spring 66 is also inclosed between the 35 cap or cover and the rear face of the valve and surrounds the boss 65^c to hold the ground face of the valve and casing in contact. The operation of this valve mechanism is analogous to that of the mechanism previously 40 described, but it differs therefrom on account of the fact that the valve is intended to oscillate instead of rotate. In the neutral position of the valve 65, that is to say, with the pin 111 midway between the two shoulders 45 112, the relief recess 65^a and 65^b will be in engagement with the ports 62 and 63, thus relieving the pipes 18 and 38 and their connections to the atmosphere through the recesses 70^a and 70^b and passage 60^a, and as 50 the openings 62^a and 63^a are over closed and solid portions of the face 61 of the valve casing, pressure fluid from the pipe 80 cannot pass through the valve mechanism. When the valve is oscillated in one direction, until arrested by the stop and shoulder 55 112 the aperture 63^a will be brought into registration with the port 63 and will therefore admit pressure fluid to the pipe 38, while if the valve is oscillated in the opposite direction until stopped, the aperture 62^a will be brought into registration with the port 62 and establish connection between the pipe 80 and pipe 18. As soon as the valve is restored to neutral position, either 60 (or both) of said passages 18 and 38 and

their connections will be relieved of pressure through the exhaust ports to the atmosphere, as before described. This form of valve I find advantageous and efficient for use as a hand actuated controlling valve 70 for compressed fluid starting mechanism for internal combustion engines, in which case the pipe 80 will ordinarily extend to the tank or reservoir of compressed air and the pipe 38 will lead to the distributor which 75 may be the form shown in Figs. 1, 2, and 3, or of some other form, and the pipe 18 will lead to a pump or air compressing device so that when the valve is moved into position to connect the pipe 18 with the 80 pipe 80, as before described, compressed air may be forced through the valve mechanism into the tank or storage receptacle.

What I claim and desire to secure by Letters Patent is:—

85

1. In a disk valve mechanism, the combination with a valve casing provided with a plane valve engaging face, provided with ports therein, forming a valve seat, and having a bearing aperture concentric with 90 and extending to said face, of an actuating shaft journaled in said bearing aperture, said shaft and casing being provided with a relief passage communicating with the atmosphere, a disk valve engaging said face 95 and provided with a port extending through the valve, and with a separate relief recess on the inner face of the valve adapted to register with a port or ports in the valve seat, and also with said relief passage, and 100 means for admitting pressure fluid into said casing adjacent to the rear face of said valve.

2. In a disk valve mechanism, the combination with a valve body provided with a 105 plane valve engaging face having ports therein, forming a valve seat, and having a bearing aperture extending through the body to said face, of a disk valve engaging said face and provided with a port extending 110 through the valve, and with a separate relief recess in the inner face of the valve, said port and recess being adapted to register with ports in the valve seat, a shaft separate from the valve mounted in said 115 bearing aperture, said shaft being provided with an annular recess connecting with the relief recess in the face of the valve, the valve body being provided with a relief passage extending to the atmosphere and communicating with the annular recess in said shaft, and means for admitting pressure fluid to the valve body adjacent to the rear 120 face of said valve.

3. In a disk valve mechanism, the combination with the valve body provided with a plane valve engaging face having ports therein, of a disk valve engaging said face and provided with an aperture extending 125 through the valve and with a separate re- 130

lief recess in the inner face of the valve, said aperture and recess being adapted to register with ports of the valve body, a shaft mounted in said valve body and operatively connected with the valve, for turning it upon its axis, said shaft being provided with an annular recess extending around the same and with a longitudinal recess communicating with the said annular recess and with the relief recess in the disk valve, said valve body being provided with a relief aperture communicating with the annular recess in the shaft.

4. In a disk valve mechanism, the combination with a valve body having a plane valve engaging face provided with ports and forming a valve seat, and having a bearing aperture concentric with and extending to said face, of an actuating shaft 20 in said bearing aperture extending into the valve body beyond said seat, a disk valve having a face to engage said valve seat, and provided with a port extending through the valve and with a relief recess in the seat 25 engaging face, said valve having a central concentric recess adapted to receive the inwardly extending end of said shaft, the said recess connecting with the relief recess, said actuating shaft being provided with an annular relief passage surrounding the same, and with a passage extending therefrom into the central recess of the valve, and said body being provided with a relief passage 30 communicating with the annular relief passage for the valve shaft and with the atmosphere, said valve casing being provided with an aperture opposite said valve seat

35

of a size sufficient to permit of the removal of the valve, a closure for said aperture, and means for admitting pressure fluid into the valve body adjacent to the rear face of the valve, and interlocking devices connecting said valve and said actuating shaft, and constructed to permit relative movement between said valve and shaft in directions longitudinally of said shaft.

5. In a disk valve mechanism, the combination with the valve body provided with a plane valve engaging surface having a plurality of ports formed therein, of a shaft 50 mounted in said valve body concentrically with said plane surface, said shaft being provided with an annular and a longitudinal recess extending therefrom to the inner end of the shaft, of a disk valve having a 55 plane face engaging the plane face of the valve body and provided with a relief passage communicating with the longitudinal recess in the shaft, said valve being also provided with apertures extending therethrough, interlocking devices for detachably connecting said shaft and valve, a removable closure for the valve body, a coil spring inclosed between said closure and the valve, a stop lug secured to the shaft, and shoulders on the valve body for engaging said lug and arresting the valve in predetermined positions.

In testimony whereof I affix my signature, in the presence of two witnesses.

FRANK E. TEN EYCK.
